UNITED STATES PATENT OFFICE.

GENTRY JONES, OF REDHOUSE, KENTUCKY; ZERELDA M. JONES ADMINISTRATRIX OF
SAID GENTRY JONES, DECEASED.

ELECTRIC MAIL-CARRIER.

1,358,557.

Specification of Letters Patent.

Patented Nov. 9, 1920.

Application filed January 6, 1919. Serial No. 269,878.

To all whom it may concern:

Be it known that I, GENTRY JONES, a citizen of the United States, residing at Redhouse, in the county of Madison and State 5 of Kentucky, have invented new and useful Improvements in Electric Mail-Carriers, of which the following is a specification.

This invention is an improved electric mail and parcel carrier especially adapted 10 for use by those who live on rural mail routes and at some distance from such routes, the object of the invention being to provide a mail and parcel system, which is electrically operated and which embodies means to automatically stop the car when the same reaches 15 the end of the line and also embodies means operated and controlled by the car doors to reverse the car when the appropriate door is opened and to enable the car to be started 20 by merely operating a clutch releasing lever after the door has been closed.

A further object of the invention is to provide an improved electric mail and parcel carrier system which utilizes ordinary 25 telephone poles in its installation, which can be readily installed at small cost, which is reliable and efficient in operation, is practically automatically controlled, and is not likely to get out of order.

With the above and other objects in view, the invention consists in the construction, combination and arrangement of devices hereinafter described and claimed.

In the accompanying drawings:

Figure 1 is a vertical sectional view 35 through the electric mail and parcel carrier constructed in accordance with my invention.

Fig. 2 is an elevation of the car partly in 40 section, and the elevated track on which the same is mounted for operation.

Fig. 3 is a transverse sectional view 45 through the invention.

Fig. 4 is a fragmentary detail view of 50 the motor.

Fig. 5 is a detail view of the switch mechanism.

Fig. 6 is a diagrammatic view.

Fig. 7 is a side elevation of the car mounted 55 upon its track.

The car or box 1 for carrying mail, or other matter, is here shown as cylindrical in form and as provided with doors 2, 2^a at its opposite ends, each door being pivotally mounted at the lower side, as at 3, and

being provided, respectively with downwardly extending arms 4, 4^a. Spring fastening devices 5 are employed to hold the doors in closed position and each door has a handle 6 at its upper side to enable the door to be readily opened.

The car is mounted on an elevated track which comprises an upper rail 7 and a lower rail 8, said rails being secured and insulated from the outer ends of supports 9, 10, the 65 said supports being bracket arms which are here shown as secured to suitable posts 11. The head of the upper rail 7 is formed by a conducting wire 12 and the head of the lower rail 8 is formed by a similar wire 13. 70

Under the center of the car is a casing 14 in which an electric motor, preferably a direct current motor, 15 is mounted, the motor shaft being indicated at 16 and projecting from one side of the casing and being provided with a miter gear 17. The casing is

provided with downwardly diverging arms 18 in which current collector wheels are mounted for rotation, said wheels being peripherally grooved and engaging the lower 80 conducting wire 13. Brackets 20 are secured on the upper side of the box or car and are provided with bearings for shafts 21, each shaft having a worm gear 22 at its outer end and a peripherally grooved current collecting wheel 23 at its inner end, the 85 wheels 23 bearing on the wire head 12 of the upper rail 7, said wheels also being insulated as at 24. The insulation between the rails 7, 8 and the supporting bracket arms 9, 10 is indicated at 25. A longitudinally arranged shaft 26 is also mounted in bearings in the brackets 20 and is provided at its ends with worms 27 which engage the worm gears 22. At the center of said shaft is a 90 miter gear 28.

A vertical shaft 29 is mounted in bearings 30 and has a miter gear 31 at its lower end which engages the gear 17 and, hence, said shaft is driven by the motor, as will be understood. A friction cone 32 is secured to the upper end of said shaft. A vertical shaft 33 is arranged above and in line with the shaft 29 and is mounted in suitable bearings 34 which are on one side of the box or 100 car. At the upper end of the shaft 33 is a miter gear 35 which engages the gear 28. A hollow frusto-conical clutch member 36 is splined on the lower portion of the shaft 33 and is held normally engaged with the 105

110

friction cone 32 by a spring 37 so that the shaft 33 is normally secured to the shaft 29 for rotation thereby, by the clutch which comprises the members 32, 36.

A line switch 38 is included in the circuit with the motor and has a pivotally mounted bar 38^a which is provided with a cam 38^b on its underside near the free end and a downwardly extending arm 38^c at the pivoted end. On the upper side of said bar, near the free end, is an upwardly extending arm 38^d which has a stud 38^e. A contact arm 38^f is pivoted at 38^g and has a roller 38^h. The terminals of said switch are indicated at 38ⁱ and spring contacts are indicated at 38^j. Springs 38^k are attached to the frame and to the bar 38^a.

The car is provided with levers 39, each of which is provided with an arm 39^a at the outer end connected thereto by a joint 39^b. Such joint enables said arm to turn in one direction, against the tension of a spring 39^c. Hangers 40 are at the ends of the line, and when the car reaches either end of the line 25 one of the levers strikes one of the hangers and is turned thereby, as said lever passes said hanger a sufficient distance to cause the arm of said stop lever to engage the stud 38^e of the bar 38^a and pivotally turn 30 said bar to a sufficient extent and in the required direction to open the line switch and hence stop the operation of the motor and the movement of the car. The joint and the spring permit the said stop lever arm 35 to turn and clear the hanger, when the movement of the car is reversed.

A reversing switch 42 is also included in the circuit with the motor and has a reversing lever 43. Said lever has a stud or pin 44 which projects from one side thereof. A link rod 45 is pivotally connected at one end to the lower end of the arm 4^a of the door 4, as at 46 and is provided at the opposite end with a slot 47, in which the stud 44 operates so that the said link rod is pivotally and slidably connected to the reversing switch lever 44. A similar link rod 48 is pivotally connected to the arm 5^a of the door 5, as at 49, has a slot 50 in which the 45 said stud 44 operates, and has a downwardly curved arm 51 at its free end and in which is a curved slot 52. A link rod 53 is pivotally connected, as at 54, to the arm 38^c of the line switch bar 38^a, and has a slot 55 near its free end. Said end crosses the curved arm 51. A stud or pin 56 connects said link rod and arm together and works in the slots 52, 55.

A vertically movable lifting element 57 has a yoke 58 which engages in an annular groove of a hub or sleeve of the clutch member 36, has a lifting pin 59, which projects from one side and also has a stop opening 60. A slide 61 is movable lengthwise on a

supporting and slide frame or base 62, said slide having a segment cam 63 on its upper side which enjoys and is slidable under the pin 59. A stud 64 projects from one side of the said cam. A link rod 65, which is bent as shown has one end pivotally connected to said stud and hence to the slide and the other end pivotally connected to the upper end of the reversing switch lever 43, as at 66. Hence when the reversing switch lever is turned in either direction the slide 75 moves therewith and the cam and the pin 39 lift the clutch member 32 and thereby disconnect the car driving gears 35, 28, 27, 22 from the motor, as will be understood. This occurs when the front door of the car is 80 opened and according to the direction in which the car is to move.

To hold the member 57 in raised, unclutched position, I provide a detent pin 67, which is forced by a spring 68 into the opening 60, with said member 57 raised. The said pin is mounted for movement in a guide 69 on a bracket 70, said bracket being secured to a support 71, which extends downwardly from the box or car. To release the 90 detent from the member 57, and hence put the car in gear, I provide a bell crank 72, which is pivotally supported at 73 and has one arm connected to the detent pin. The other arm of the bell crank is loosely pivotally connected to the inner ends of a pair 95 of levers 74, 75, which extend to opposite ends of the car and are mounted as shown.

In order to start the box or car, it is only necessary to open one of the doors, according to the direction in which the car is to run. This, by means hereinbefore described, closes the line switch, lifts the clutch and reverses the leads to the motor and sets the motor in operation in the required manner. 100 The operator, then, by means of one of the clutch releasing levers 74, 75, which extends to the ends of the car, causes the bell crank 72 to operate the pin 67 and disengage the latter from the opening of the clutch 57, 110 whereupon the spring 37 engages the clutch member 36 with the clutch member 32 thereby connecting the driving gear of the car to the motor and, hence, the car is driven to the other end of the line. As the car 115 reaches such terminal the stop hanger 40 at such terminal and one of the stop levers 39 coat as before described to open the line switch so that the car is stopped and automatically controlled. The rear door can 120 be opened without affecting the switch operating mechanism, this being permitted by the slots 47, 50, as will be understood. When the car thus stops at either end of the line current is switched on an electro-magnetic 125 impulse motor 58 which rings a signaling bell 59 for an appropriate period of time, usually one-half of a minute.

While I have herein shown and described a preferred embodiment of my invention, I would have it understood that changes may be made in the form, proportion and construction of the several parts without departing from the spirit of my invention and within the scope of the appended claims.

Having described the invention, I claim:

1. In an electric mail carrier system of the class described, an electric car having a line switch, a reversing switch, a door, and means to cause the door to operate said switches when the door is opened or closed.
2. In an electric mail carrier system of the class described, a car having a door, driving means including a clutch, and means operated by the door to move the clutch to disengaging position when the door is opened.
3. In an electric mail carrier system of the class described, a car having a door, driving means including a clutch, means operated by the door to move the clutch to disengaging position when the door is opened, and means to release the clutch when the door is closed.
4. In an electric mail carrier system of the class described, an electric car having a switch and a stop lever to open the switch, said lever having a member yieldable in one direction, and relatively fixed means arranged in the path of said yieldable member to engage the same and cause said lever to open the switch.
5. In an electric mail carrier system of the class described, a car having a line switch, a door operated reversing switch, means to open the line switch when the car reaches a terminal, and means to cause the reversing switch to close the line switch when the reversing switch is reversed.
6. In an electric mail carrier system of the class described, a car, doors at the opposite ends of the car, a reversing switch having a movable member, and link rods each connecting one of the doors to said reversing switch member, and arranging each door for

movement independently of said switch member, when the other door is closed.

7. In an electric mail carrier system of the class described, a car having a door, driving means for the car, a switch operated by the door, and means also operated by the door, to put the car out of gear.

8. In an electric mail carrier system of the class described, a car, pivoted doors at opposite ends of the car and each having an arm, a reversing switch having a movable element, link rods pivotally connected to the arms and each having a slot, and a pivot connecting said link rod to the said movable element and arranged for movement in the slots of said rods.

9. In an electric mail carrier system of the class described, a car, pivoted doors at opposite ends of the car and each having an arm, a reversing switch having a movable element, link rods pivotally connected to the arms and each having a slot, a pivot connecting said link rods to the said movable element and arranged for movement in the slots of said rods, driving means for the car, means operated by said movable member to put the car out of gear, and a line switch having a controlling member connected to and operated by one of said link rods.

10. In an electric mail carrier system of the class described, a car, pivoted doors at opposite ends of the car and each having an arm, a reversing switch having a movable element, link rods pivotally connected to the arms and each having a slot, a pivot connecting said link rods to the said movable element and arranged for movement in the slots of said rods, driving means for the car including a clutch member, a detent for the clutch member, means operated by the movable element of the reversing switch to move the clutch member to disengaged position, and means to release said switch member.

In testimony whereof I affix my signature.
GENTRY JONES.
